2 Claims. (Cl. 103—271)

ABSTRACT OF THE DISCLOSURE

A device for introducing a first fluid into a stream containing a second fluid by the use of a venturi effect including an outer pipe having an inner pipe inside of the outer pipe, and a passageway through the outer pipe in communication with the interior of the inner pipe. The outer pipe has an internal shoulder toward and away from which the inner pipe is movable to adjust the portion of the fluid flowing between the pipes.

This invention relates to the mixing of flowing fluids, and more particularly to a device for pumping, proportioning and mixing two or more fluids over a wide range of flow rates and pressures at maximum efficiency.

The device of the present invention will have a large scope of application and therefore should not be limited to those specifically disclosed herein. However, the invention has been found especially useful for mixing liquid fertilizer with water for distribution through lawn sprinklers.

Conventional aspirator type devices are impractical as liquid fertilizer mixing devices for sprinkler systems as a different kind of device must be employed with each different kind of sprinkler system. This is due to the fact that a smaller constriction, or venturi, is required for smaller systems, whereas the small venturi in a larger system creates such a small constriction that insufficient pressure is received at the sprinkler heads.

In accordance with the device of the present invention, the above-described and other disadvantages of the prior art are overcome by providing a variable fluid proportioner.

In accordance with the invention, a main passageway is provided with an auxiliary passageway connected thereto in a manner to divert at least a portion of fluid flowing in the main passageway. A suction passageway is then connected to the auxiliary passageway and means are provided to adjust the portion of fluid diverted through the auxiliary passageway.

In accordance with the foregoing, a by-pass is formed in the main passageway and the device of the present invention may be adjusted for a sprinkler system of any size or number of sprinkler heads.

Although the device of the present invention will be found to be useful in distributing liquid fertilizer, insecticide and other chemicals for use in the horticulture art, the present invention is not limited to these particular uses. It is, in fact, a salient feature of the present invention that it can be employed to induce a secondary stream of any fluid into a primary or main stream of fluid. The primary and secondary streams of fluids are then mixed in a predetermined and adjustable ratio.

The above-described and other advantages of the present invention will be better understood from the following description when considered in connection with the accompanying drawings.

In the drawings which are to be regarded as merely illustrative:

FIG. 1 is a longitudinal sectional view of a variable fluid proportioner constructed in accordance with the present invention;

2

FIG. 2 is a transverse sectional view therethrough taken on the line 2—2 shown in FIG. 1 with the adjustment mechanism turned 90 degrees;

FIG. 3 is a longitudinal sectional view of the device taken on the line 3—3 shown in FIG. 1;

FIG. 4 is a longitudinal sectional view of an alternative embodiment of the present invention;

FIG. 5 is a transverse sectional view taken on the line 5—5 of the device shown in FIG. 4;

FIG. 6 is a longitudinal sectional view of still another embodiment of the present invention;

FIG. 7 is a transverse sectional view of the device of the present invention with an adjustment turned 90 degrees, but taken on the line 7—7 shown in FIG. 6; and

FIG. 8 is a longitudinal sectional view of the device taken on the line 8—8 shown in FIG. 6.

In the drawing in FIG. 1, one embodiment of the invention is illustrated at 10 including a main body 11 having an auxiliary body 12 slidably therein on fins 13.

20 Auxiliary body 12 has an inlet conical surface 14 and an outlet conical surface 15. Body 12 is shiftable from the solid line position shown at 12 to the dotted line position shown at 12'. Main body 11 has an opening 16 which is closed by a rotary plug 17 against which an O-ring seal 18 is pressed by a fitting 19. Plug 17 has an eccentric hole 20 into which a fitting 21 is located, fitting 21 being threaded to auxiliary body 12 and having an opening 22 to form the suction inlet.

When plug 17 is turned 90 degrees from the position shown, in FIG. 1, auxiliary body 12 will move half way between the positions indicated at 12 and 12'. Body 21 will then appear in the position as shown in FIG. 2. Plug 17 may be turned 180 degrees from the position shown in FIG. 1. In this case, body 21 will move from the solid line position therein indicated at 21'. The amount of rotation between 0 and 180 degrees given to plug 17 will determine how much fluid flows around the outside of the auxiliary body 12 between fins 13. This will also determine the amount of suction that the device of the invention will develop. In general, a minimum amount of suction is desired so that the device 10 will introduce as little pressure head loss as possible. The minimum diameter of the auxiliary body 12 will be of a size to fit the smallest type of installation. In general, body 11 will be threaded at its ends as indicated at 23 and 24 to fit a standard $\frac{3}{4}$ -inch pipe thread.

Another embodiment of the invention is shown in FIGS. 4 and 5. In this embodiment, a main body 24 is provided with a smaller body 25 inside of it. Body 25 is constructed similarly to body 12. However, body 25 is not movable inside of body 24. Body 25 has a plug 26 fixed to it to hold it centrally in body 24. A suction tube 27 is threaded into plug 26. Tube 27 has an opening 28, as before, which is in communication with the interior of body 25. A nut 29 is threaded onto tube 27 and holds a gasket 30 tightly against body 24.

The amount of water which is permitted to pass between the external surface of body 25 and the internal surface of body 24 is adjusted by moving a cylinder 31 toward and away from the right end of body 25 as viewed in FIG. 4. Cylinder 31 has sealing O-rings 32 and 33. A wing bolt 34 is threaded into the body of cylinder 31. Wing bolt 34 projects through a longitudinal slot 35 in body 24. The length of possible travel of cylinder 31 is indicated in dotted lines at 31'. When cylinder 31 takes the position shown at 31', wing bolt 34 is moved to the position indicated at 34' in FIG. 4.

Still another embodiment of the invention is indicated at 36 in FIG. 6. This embodiment is similar to that shown in FIG. 1 to the extent that all parts are identical with the exception of suction tube 21. In lieu thereof, a plastic tube 37 is provided in a plug 17'. Tube 37 is straight in the

positions shown in solid lines in FIGS. 6 and 8. When plug 17' is turned 90 degrees, tube 37 bends slightly as shown in FIG. 7. When plug 17' is turned 180 degrees, the inner body 12" moves from the solid line position to the dotted line position indicated at 12".

As stated previously, common venturi type devices are impractical as liquid fertilizer dispensing devices as they must be engineered individually for each kind of sprinkler system. This is due to the fact that a smaller venturi is required for small systems, whereas a small venturi in a larger system creates a pressure head loss which is intolerable. Note will be taken that all of the devices of the present invention described hereinbefore are adjustable. This means that each may be adjusted for a minimum suction. This makes it possible to use any of the devices in a small or large sprinkler system without having the intolerable pressure head loss which was attendant upon the use of prior art venturis. In particular, in FIG. 1 the amount of suction the device produces can be adjusted by rotating plug 17. The same is true of the device shown in FIG. 6. The device shown in FIG. 4 has the same adjustment in that movement of cylinder 31 controls the amount of fluid which is passed through the smaller body 25.

From the foregoing, it will also be appreciated that all of the embodiments of the invention may be used to mix together not only a plurality of fluids disclosed herein, but also any other fluids by inducing one into another. What is important in this case is that the fluids may be mixed in a portion which is adjustable with the rotational position of plug 17 in FIGS. 1 and 6 and with the axial position of cylinder 31 in FIG. 4.

Although only three specific embodiments of the present invention have been described and illustrated herein, many changes and modifications will of course suggest themselves to those skilled in the art. Three embodiments have been selected for this disclosure for the purpose of illustration only. The present invention should therefore not be limited to the embodiments so selected, the true scope of the invention being defined only in the appended claims.

What is claimed is:

1. A variable fluid proportioner comprising: a larger

main pipe having an inlet passageway, an outlet passageway, and a hole through the wall thereof between said passageways; a smaller auxiliary pipe inside said main pipe at said hole, said auxiliary pipe having longitudinal fins extending radially therefrom to said main pipe to guide longitudinal movement of said auxiliary pipe inside of said main pipe, said auxiliary pipe having an outside diameter smaller than the inside diameter of said main pipe and being spaced therefrom to allow fluid to flow in the space between said pipes, said main pipe having a shoulder therein, said auxiliary pipe being movable axially in said main pipe toward and away from said shoulder to vary the amount of fluid flowing in said pipes; a round plug rotatable in said main pipe hole; an eccentric suction tube extending from said auxiliary pipe through said plug spaced from the axis thereof, said tube being rotatable in said auxiliary pipe to move the latter axially upon rotation of said plug.

2. A variable fluid proportioner comprising: a larger main pipe; a smaller auxiliary pipe inside said main pipe, said auxiliary pipe having longitudinal fins to hold it slideable centrally within said main pipe, said main pipe having a transverse opening therethrough at the position of said auxiliary pipe; a rotatable body in said opening, said body having a hole therethrough, said auxiliary pipe having a transverse hole therethrough; and a flexible tube-like body connecting said holes, said rotatable body hole being eccentric to the axis of said body.
